Primary Examiner—Raphael Barkai*(74) Attorney, Agent, or Firm*—Brinks Hofer Gilson & Lione(57) **CLAIM**

We claim the ornamental design for a television receiver, as shown and described.

DESCRIPTION

FIG. 1 is a top perspective view of a television receiver of the present invention;

FIG. 2 is a front view thereof;

FIG. 3 is a rear view thereof;

FIG. 4 is a first side view thereof, wherein the second side view is a mirror image thereof;

FIG. 5 is a top view thereof;

FIG. 6 is a bottom view thereof; and,

FIG. 7 is a first side view thereof, wherein the television receiver is in a first alternative position.
